(57) **CLAIM**

The ornamental design for a charging connector for electric vehicle, as shown and described.

DESCRIPTION

FIG. 1 is a front, top and left side perspective view of a charging connector for electric vehicle showing our new design;

FIG. 2 is a front, bottom and left side perspective view thereof;

FIG. 3 is a front, top and right side perspective view thereof; FIG. 4 is a front, bottom and right side perspective view thereof;

FIG. 5 is a front elevation view thereof.

FIG. 6 is a rear elevation view thereof.

FIG. 7 is a top plan view thereof.

FIG. 8 is a bottom plan view thereof.

FIG. 9 is a left side elevation view thereof; and,

FIG. 10 is a right side elevation view thereof.

The portions of the article shown in broken lines are for the purpose of showing environmental structure only and form no part of the claimed design.
